UNITED STATES PATENT OFFICE.

GIUSEPPE CARMELO LARAIA, OF NEW YORK, N. Y.

HEADREST FOR BARBER OR LIKE CHAIRS.

Application filed June 9, 1921. Serial No. 476,173.

To all whom it may concern:

Be it known that I, GIUSEPPE CARMELO LARAIA, a citizen of the United States of America, residing in the borough of Manhattan, city, county, and State of New York, have invented certain new and useful Improvements in Headrests for Barber or like Chairs, of which the following is a specification.

10 This invention relates to head-rests for barber or like chairs, and aims to provide improvements therein.

The invention provides simple and effective means for fastening the head-rest 15 15 in various positions around its point of support.

The invention further provides simple and effective means for adjusting the height of the head-rest, and which is combined with 20 the back-rest of the chair in such manner as to have a pleasing appearance.

The invention further provides combinations and subcombinations of parts, hereinafter set forth, for effecting in an improved manner the purposes of the invention.

An embodiment of the invention is illustrated in the accompanying drawings, wherein—

30 Figure 1 is a view in vertical section of a head-rest, and so much of the back-rest of a chair as is necessary to illustrate the combination;

Fig. 2 is a vertical section at right angles 35 to the view in Fig. 1;

Fig. 3 is a view similar to Fig. 2, illustrating the preferred form of embodiment of the locking means for the head-rest;

Fig. 4 is a view on the line IV—IV, 40 Fig. 1;

Fig. 5 is a section on the line V—V, Fig. 3.

Referring to said drawings, numeral 10 45 designates a back-rest comprising a frame 11, and 12 designates a head-rest. The head-rest conveniently comprises a head-rest proper, 13, and a post 15, preferably supported by, and adjustable vertically upon, the said back-rest 10. To this end the frame 50 11 of the back-rest is conveniently provided with an inwardly-projecting flange 17, and the said flange 17, as well as the upper side of the back-rest frame 11, are provided with slots 19, 20, through which the post 15 slides, 55 and in which it is guided. Means are pro-

vided for holding the post 15 at various heights of projection beyond the back-rest, and for this purpose the post 15 is conveniently provided with a series, 22, of ratchet teeth, and a pawl 24 on the inside of the back-rest is provided for engaging the said ratchet teeth 22 of the post. The back-rest frame 11 is conveniently provided with an opening 26 through which the pawl 24 may be reached and pressed to release it from engagement with the teeth 22. The end of the pawl 24 opposite the opening 26 is conveniently provided with a hollow projection 27 which projects into the opening 26, and a spring 29 for pressing the pawl 24 into engagement with the teeth is conveniently located and retained in the hollow part of the said projection 27. The pawl 24 is conveniently pivoted to a lug plate 31, as indicated at 33, which lug plate is conveniently secured 75 to the inner side of the back-rest frame 11, as indicated at 34, Fig. 4. The edge portion 36 of the opening 26 in the back-rest frame 11 constitutes an abutment or stop for engaging the pawl 24, for limiting its pivotal 80 movement, when the post 15 is withdrawn. The lug plate 31 acts as a stop for the pawl 24, when pressed inward.

A pivotal connection 40 is conveniently provided between the head-rest proper and 85 the post 15. This joint is conveniently in the form of a hinge or knuckle joint, the parts of which are connected by a pivot pin 41. A stud 43 having lateral frame extensions 44 is preferably interposed between the 90 head-rest 13 and the pivotal connection 40. Shoulders 45 and 46 on one of the parts of the joint (the post 15, as here shown) limit the turning of the head-rest around the pivotal connection in such manner that it is 95 prevented from striking or coming into contact with the back-rest, and thereby injuring the appearance of the parts.

Means 50 are preferably provided for locking the head-rest 13 in various positions around said pivotal connection 40. This means preferably comprises a manipulating part or handle 52 extending to one side of the head-rest, and a locking pin 54 conveniently mounted in the stud 43 and 100 engaging the post 15, as by means of sockets 55 formed in the disk 53 of the joint 40 which is formed upon the said post 15. The locking pin 54 is conveniently pressed 105 into engagement with the sockets 55 by a 110

- spring 57 bearing against a collar 56 and housed in an enlarged bore 59 in the stud 43. A bushing 60 in the end of the bore 59 provides an abutment for the other end 5 of the spring and a guide for the upper end of the locking pin 54. The locking pin 54 is conveniently provided with a head or collar 63, and this is conveniently engaged by a cam 65 directly, as shown in Figs. 1 10 and 2, or indirectly through a lever, 67, as shown in Fig. 3. The collar 63 may be in the form of a nut, threaded in the locking pin, and fixed against movement by a lock nut 68, as shown in Fig. 3. This construction admits of adjusting the time of contact between the collar 63 and lever 67. A flat spring 70 is provided for holding the end of the lever against the cam 65. This spring acts to automatically throw the manipulating parts to initial position when the manipulating piece 52 is released. The cam 65 is conveniently connected to the manipulating part or handle 52 by means of a rock shaft 80. In the construction 20 shown in Fig. 3, the cam 65 is conveniently provided on its under side with a flat 71, so as to maintain a corresponding position in contact with the lever 67. Moreover, the arrangement of the parts is preferably such 30 that when the locking pin 54 is pressed by the spring 57 completely into engagement with one of the sockets 55, the adjacent part of the cam 65 in the construction of Fig. 2, or the adjacent end of the lever 67 in the 35 construction of Fig. 3, is out of contact with the collar 63, so that no resistance is offered by the manipulating mechanism to the action of the spring in pressing the locking pin into engagement with the sockets 55.
- 40 To change the position of adjustment of the head-rest around its pivotal connection, it is simply necessary to turn the manipulating part or handle 52 in one direction or the other, causing the cam 65, either directly or 45 through the lever 67, to raise the locking pin from a socket 55. The head-rest is then moved around the pivot 41 to the desired position, whereupon the manipulating part or handle 52 is released or turned back, 50 thereby allowing the spring to press the locking pin into another of the sockets 55.
- To adjust the height of the head-rest, the projection 27 of the pawl 24 is pressed, and the post 15 raised or lowered to the desired 55 height, and the pawl thereupon released to engage one of the rack teeth. With rack teeth of the character shown, it will not be necessary to press the pawl 24 in raising the post.
- 60 The inventive ideas may receive other embodiments than those herein specifically illustrated and described.
- What is claimed is:
1. In combination, a barber or like chair head-rest, a pivotal connection for said

head-rest, and means for locking said head-rest in different positions around said pivotal connection, said means comprising a locking pin, operating means mounted transversely of said locking pin and projecting 70 at the side of said head-rest, said operating means comprising a rock shaft, and a part adapted to engage said locking pin for sliding said pin into and out of locking position. 75

2. In combination, a barber or like chair head-rest, a pivotal connection for said head-rest, a locking pin for locking said head-rest on said pivotal connection, a spring for pressing said pin to its locking position, operating means mounted transversely of said pin and projecting at the side of said head rest and a connection between said operating means and locking pin for sliding said pin out of locking position, 80 said operating means being disconnected from said locking pin in locking position of the parts, whereby said spring may act unhindered to press said pin to its locking position. 85

3. In combination, a barber or like chair head-rest, a pivotal connection for said head-rest, and means for locking said head-rest in different positions around said pivotal connection, said means comprising a locking pin, operating means projecting at the side of said head-rest, said operating means comprising a rock shaft, a cam on said rock shaft, and a lever operated by said cam adapted to reciprocate said locking pin 100 into and out of locking position. 90

4. In combination, a barber or like chair head-rest, a pivotal connection for said head-rest, a locking pin for locking said head-rest on said pivotal connection, a spring for pressing said pin to its locking position, and operating means mounted transversely of said pin and projecting at the side of said head-rest, a connection between said operating means and locking pin 105 for sliding said pin out of locking position, and a spring pressing on a part of said operating means for moving said operating means to initial position when released, and for so maintaining it, whereby said operating means may be disconnected from said locking pin in locking position of the parts, and said first mentioned spring may act unhindered to press said locking pin to its locking position. 110

5. In combination, a barber or like chair head-rest, a pivotal connection for said head-rest, and means for locking said head-rest in different positions around said pivotal connection, said means comprising a locking pin, operating means mounted transversely of said locking pin and projecting at the side of said head-rest, a connection between said operating means and locking pin for sliding said pin into and out 125

130

of locking position, and a collar on said pin adjustably mounted with respect to said operating means.

6. In combination, a barber or like chair head-rest, a pivotal connection for said head-rest, a locking pin for locking said head-rest on said pivotal connection, a spring for pressing said pin to its locking position, and a lever for sliding said pin out of locking position, said lever being out of contact with said locking pin in locking position of the parts, whereby said spring acts unhindered to press said locking pin to its locking position.
- 15 7. In combination, a barber or like chair head-rest, a pivotal connection for said head-rest, and means for locking said head-rest in different positions around said pivotal connection, said means comprising a locking pin, operating means projecting at the side of said head-rest, said operating means comprising a rock shaft, and a cam on said rock shaft, a lever operated by said cam adapted to reciprocate said locking pin, and a spring for pressing said locking pin to its locking position, said lever being out of contact with said locking pin in locking position of the parts, whereby said spring acts unhindered to press said locking pin to its locking position.
- 20 8. In combination, a barber or like chair head-rest, a pivotal connection for said head-rest, a hollow stud forming a part of said pivotal connection having radiating arms forming the supporting structure for said head-rest, and means for locking said head-rest on said pivotal connection, said means comprising a locking pin arranged longitudinally in said stud, an operating means mounted on one of said radiating arms and projecting at the side of said head-rest, and a connection between said operating means and locking pin for sliding said pin into and out of locking position.
- 25 9. In combination, a barber or like chair head-rest, a pivotal connection for said head-rest, a hollow stud forming a part of said pivotal connection having radiating arms forming the supporting structure for said head-rest, and means for locking said head-rest on said pivotal connection, said means comprising a locking pin arranged longitudinally in said stud, an operating means mounted on one of said radiating arms and projecting at the side of said head-rest, and a connection between said operating means and locking pin for sliding said pin into and out of locking position.

30 10. In combination, a barber or like chair head-rest, a pivotal connection for said head-rest, and means for locking said head-rest in different positions around said pivotal connection, said means comprising a locking pin, operating means projecting at the side of said head-rest, said operating means comprising a rock shaft, and a cam on said rock shaft, and a lever operated by said cam adapted to reciprocate said locking pin, a collar on said locking pin adapted to be engaged by said lever, and means for adjusting the position of said collar with respect to said lever.

35 11. In combination, a barber or like chair head-rest, a pivotal connection for said head-rest, a hollow stud forming a part of said pivotal connection having radiating arms forming the supporting structure for said head-rest, and means for locking said head-rest on said pivotal connection, said means comprising a locking pin arranged longitudinally in said stud, an operating means mounted on one of said radiating arms and projecting at the side of said head-rest, and a connection between said operating means and locking pin for sliding said pin into and out of locking position.

40 12. In combination, a barber or like chair head-rest, a pivotal connection for said head-rest, a hollow stud forming a part of said pivotal connection having radiating arms forming the supporting structure for said head-rest, and means for locking said head-rest on said pivotal connection, said means comprising a locking pin arranged longitudinally in said stud, an operating means mounted on one of said radiating arms and projecting at the side of said head-rest, and a connection between said operating means and locking pin for sliding said pin into and out of locking position.

45 13. In combination, a barber or like chair head-rest, a pivotal connection for said head-rest, a hollow stud forming a part of said pivotal connection having radiating arms forming the supporting structure for said head-rest, and means for locking said head-rest on said pivotal connection, said means comprising a locking pin arranged longitudinally in said stud, an operating means mounted on one of said radiating arms and projecting at the side of said head-rest, and a connection between said operating means and locking pin for sliding said pin into and out of locking position.

50 14. In combination, a barber or like chair head-rest, a pivotal connection for said head-rest, a hollow stud forming a part of said pivotal connection having radiating arms forming the supporting structure for said head-rest, and means for locking said head-rest on said pivotal connection, said means comprising a locking pin arranged longitudinally in said stud, an operating means mounted on one of said radiating arms and projecting at the side of said head-rest, and a connection between said operating means and locking pin for sliding said pin into and out of locking position.

55 15. In combination, a barber or like chair head-rest, a pivotal connection for said head-rest, a hollow stud forming a part of said pivotal connection having radiating arms forming the supporting structure for said head-rest, and means for locking said head-rest on said pivotal connection, said means comprising a locking pin arranged longitudinally in said stud, an operating means mounted on one of said radiating arms and projecting at the side of said head-rest, and a connection between said operating means and locking pin for sliding said pin into and out of locking position.

16. In witness whereof, I have hereunto signed my name.

GIUSEPPE CARMELO LARAIA.
